2,606,865

SELF-ADJUSTING AIRTIGHT DOOR

Pierre Eugène Henri Forsans, Paris, France

Application February 26, 1948, Serial No. 11,093
In France December 31, 1946Section 1, Public Law 690, August 8, 1946
Patent expires December 31, 1966

2 Claims. (Cl. 202—248)

1

My invention, which can be applied to coke-ovens and to any other system of oven, has for its object to provide, on the one hand, a novel air-tight door device, in which the pressure of the knife-edges against the joint surface is automatically obtained by the bending caused in the door as it assumes the shape of the suitably curved surface of the casing, and, on the other hand, various improvements of detail in the same doors.

In order to make my invention clearly understood, and only for demonstration purposes, a drawing has been appended to the present specification. In said drawing:

Fig. 1 is a front elevation of a general arrangement of a door.

Fig. 2 is a side view of the door, in vertical section along the line AA of Fig. 1.

Fig. 3 shows, on a larger scale, at the top, a fractional vertical section along the line BB of Fig. 1 and at the bottom, a fractional vertical section along the line CC of Fig. 1.

Fig. 4 shows, on an enlarged scale, a fractional horizontal section along the line DD of Fig. 1.

Fig. 5 is a fractional section showing a modification of the door joint, and

Fig. 6 is a side view of Fig. 5.

Figs. 7, 8 and 9 are fractional sections showing various modifications of the door joint and of the device for adjusting and fixing the door-casing.

In Figs. 1, 2, 3 and 4, the front face of the jamb is protected on the outside by a metal plate 2, of sheet steel for example, which is held in known manner by the anchoring 3; in front of the mouth of the oven is mounted a door-casing 4, which forms a complete frame, is attached to the plate 2 by means of the bolts 5 and is in contact with the splayed portion by means of the asbestos pads 6; the casing 4 is provided with two bearing surfaces 7 and 8 which are suitably adapted to their function and which, by construction, are located at a fixed distance from one another; in the figures, the lower bearing surface 7 does not exist on the lower cross member of the casing on a level with the hearth 9 of the oven, but it may exist at this point, but this would make it necessary to provide a special device for the sole of the coke guide.

The door comprises a metal plate 10, preferably of sheet steel, which is reinforced on the outside with bars 11 forming a frame which is both strong and flexible; said frame supports, in the usual manner, members 12 which are generally made of cast-iron and which are spaced vertical-

2

ly, said members supporting the refractory lining 13 which is in this case formed by superposed independent elements which are separated by free joints, in such a manner that the whole frame 5 remains flexible to the desired and necessary extent.

The frame 10—11 is provided at the top with two hangers 14 which suspend the frame to the cradles 15 which are provided with inlet guides 10 and are securely fixed in front of the front wall of the oven, as known; each of the hangers is attached to its corresponding bar 11 by means of a pin 16 about which it can swing by the action of a screw-jack 17 which is adapted to rotate in the wing of the bar 11 and to screw into a suitable nut of 14; finally, a bolt 18 is mounted in a slot of the hanger as described hereinafter.

At its lower part, the frame supports a known type of locking system by means of screws, which 20 comprises a nut 19 which is fixed to the frame and in which moves a screw 20 which is actuated by means of a square 21 and which supports by 25 means of a swivel a cross member 22, the two ends of which are adapted to engage in hooks 23 which are in turn secured to the door-casing 4; it is thus possible to lock the frame against the casing as required; however, according to the 30 invention, the device is provided with an essential improvement which enables the cross member to be moved in either direction according to the movement of the screw 20 after loosening, thereby enabling the cross member to be disengaged from its hooks or to be re-engaged automatically therein, the screw 20 in this case being 35 actuated by suitable mechanical means which drive the square 21 and are fixed to the door removing machine; the improvement comprises producing a sufficient adhesion of the cross member 22 on the swivel 24 of the screw 20, by means 40 of the spring 25 which is compressed by the washer 26 pinned on 20—21; any other device fulfilling the same purpose, i. e. enabling mechanical locking and unlocking to be effected by the 45 door removing machine, comes within the scope of the invention.

The frame 10—11, which is internally lined with an asbestos cushion 27, supports the knife-edge frame 28 which comprises a channel iron, the outer wing of which forms a joint knife-edge which is pressed against the portion 8 of the door-casing 4 as known, whereas the inner wing acts as an abutment for a flexible dust screen 29 made of sheet steel or other material, which is locked by means of an asbestos packing 50 30 in a suitable groove of the lining 13 and the

supports 12; said screen 29 forms a concentric frame to the knife-edge frame and its free end is adapted to bear against the bearing surface 8 of the casing 4 in order to prevent any deposit on said bearing surface 8 of dust or solid particles from the oven, which are liable to impair the efficient pressure of the knife-edge 28 against its bearing surface 8.

Finally, the frame 10-11 also supports the fines screen 31 comprising one or a plurality of superposed steel plates or the like having a certain flexibility, which forms a frame around the refractory lining 13 on three sides thereof and is locked by the packing 32 in a suitable groove of 13 and of the supports 12; the free end of the screen 31 is adapted to bear against the second bearing surface 7 of the casing 4; optionally, the screen 31 may be completed under the lining 13 by a flat asbestos or other plait 33 which is suspended to the lower lining support and is adapted to rub against the sole-plate of the oven.

Thus, any pressure of the door 10-11, which is suspended at 14-15 and locked at 22-23, against the casing 4, automatically produces a contact of the frames 28 and 29 with the bearing surface 8, and of the frame 31 with the bearing surface 7, so that simultaneously the fines contained in the cell of the oven are stopped by the screen 31, the bearing surface 8 is protected by the screen 29 from any deposit of solid substances from the oven, and finally gas-tightness is ensured by the knife-edge 28 which is pressed against the suitable bearing surface 8.

In the known systems, the necessary pressure of the knife-edge 28 against its bearing surface 8 is obtained by means of adjusting and pressure screws which bear on 10 and press against the wing of the knife-edge 28. This screw device is not essential, provided that, in accordance with the present invention, the door-casing is given a suitable domed curvature and the door is pressed against it so as to constrain said door to follow said domed curvature so that the resilient bending of the door corresponds to the necessary pressure for producing the air-tightness of the knife-edge 28 against its seat 8.

For this purpose, the fixing of the casing 4 in front of the splayed portion of the oven is such that the bolts 5 which are attached to the member 2 comprise a screw-threaded stem passing through the eyes of 4, and two nuts 34, the suitable actuation of which enables the casing 4 to be given the suitable domed curve, a side view of which is shown in Fig. 2. The frame 10-11 which is engaged at 14-15 and locked at 22-23 automatically bends and assumes the curvature which is produced and adjusted in the casing, in such a manner that the knife-edge 28 is pressed against its bearing surface 8 with the necessary pressure for obtaining efficient air-tightness; it will be readily understood that the screens 29 and 31 exactly follow the curvature of the frame and of the knife-edge and are in turn automatically pressed against the parallel curved bearing surfaces 8 and 7 of the casing 4, so that the door is constantly and automatically adjusted by the sole fact that the door bends and assumes the suitable curvature of the casing.

The curvature of the casing can be kept constant and adjusted by the action of the nuts 34, whatever the deformation of the face plate 2; similarly, the bending of the door is adjusted both by the action of the jack 17 on the hanger which is pivoted at 16 and by the locking means 22-23 which can be tightened as required; if

necessary according to the position of the locking means at the bottom of the frame, the lower part of the plate 10 may be pressed against the door-casing by means of screws 35 which bear against the cross member 36 connecting the two uprights 11 to one another. It is not essential for these adjustments to be effected frequently and the door-casing 4 is quite capable of supporting some deformations of the front wall until the instant when the limit of elastic bending of the frame 10-11 is exceeded and the air-tightness of the door is impaired; it is also possible to damp the effects of the deformation of the front walls of the oven for example by interposing resilient washers or springs between the nuts 34 and the eyes of the door-casing.

In Figs. 5 and 6, which show a modification of the joint device, the channel-shaped frame 28 bears as before against the bearing surface 8 of the casing 4, at the same time as the dust screen 29, which is fixed in the lining 13; the frame plate 10 is also provided with its asbestos lining 27 whereas the frame 28, which is mounted on a flexible plate 37 protected by an asbestos sheet 38, is urged by the frame 10 by means of an undulating spring 39 extending all round the frame, whereby the pressure device of 28, at 8, is made more flexible than in the arrangement of Fig. 4. It would also be possible, in this arrangement, to replace the undulating spring 39 by screws spaced all round a frame as is known, or to provide them with springs as described, for example, in applicant's French Patent No. 853,827 of November 16, 1938.

In Fig. 7, the door-casing is fixed to the protecting plate 2 of the front wall by means of screws 40 directly screwed into 2, shims 41 of adjustable thickness being interposed according to requirements; the frame plate 10 is provided with its asbestos cushion 27 against which rests a channel-shaped knife-edge 23 (identical to that of Fig. 4) in which is housed another channel-shaped knife-edge frame 42 of smaller size which rests in 28, on one side by means of the undulating spring 44 (similar to 39 of Fig. 6) so that by the effect of the bending of 44, the two ridges of 28 and 42 simultaneously bear against the bearing surface 8 of the casing 4; the dust screen 29 completes the device of the two independent knife edges 28 and 42.

In Fig. 8, the mounting of the casing 4 on the plates 2 is identical to that of Fig. 7, but the double knife-edge 28-42 is replaced by a knife-edge supporting frame 45 containing an assembly of two independent knife-edges receiving the pressure by means of an undulating spring (similar to 39 and 44 hereinbefore) already described in applicant's French Patent No. 918,246 of August 2, 1945.

Finally, in Fig. 9, the door-casing is adjusted on the plate 2 by means of screws 40 which are directly screwed into 2 and are provided with a lock-nut 46, whereas the door joint device is reversed owing to the fact that the knife-edge 47 is fixed to the bearing surface 8 of the casing 4 and its ridge forms a seal against the plate 10 of the door; the dust screen 29 completes the system by bearing against the free portion of the bearing surface 8, as previously; it would also be possible to mount, instead of the single knife-edge 47, a system of multiple knife-edges, for example as shown in Figs. 7 and 8 hereinbefore, or otherwise, and to provide the frame 10 with an auxiliary bearing surface fixed to a flexible metal plate as for example the knife-

edge 28 of Fig. 5; it would also be possible to add the undulating spring 39 or the screws with springs spaced round the frame in such a manner as to impart flexibility to the knife-edge bearing surface as mentioned in respect of Fig. 5 hereinbefore, with reference to the knife-edge 28.

These various modifications show different embodiments which nevertheless remain within the scope of the invention, its being possible to fit any system of knife-edge joint to the flexible frame 10-11; similarly, said flexible frame may be constructed in any manner, and the same applies to the door-casing with a double bearing surface, but all these various constructions or combinations of the elements of the invention with other known or novel elements, remain within the scope of the invention in so far as the principles of my invention are applied thereto.

I claim:

1. A coke oven comprising an outer metal protecting plate, a door casing having a concave curvature toward the inside of said oven secured to said plate by fastening means, said fastening means comprising a plurality of adjusting nuts and bolts cooperating with said plate to adjust the curvature of said casing, an inner and an outer bearing surface formed on said door casing, a door having a concave curvature toward the inside of said oven engaging said door casing, said door including vertical bars, a flexible plate rigidly connected to said bars, vertically spaced members attached to said plate, and a refractory lining supported by said spaced members, attaching means located at the upper end of said door, clamping means located at the lower end of said door, said clamping means forcing said door against said door casing thereby causing the flexible plate on said door to assume the configuration of said door casing, and sealing means disposed between said door and door casing, said sealing means including a flexible screen locked in said refractory lining and abutting against the outer bearing surface of said door casing, and means mounted on said flexible plate forcing said flexible screen against said outer bearing surface of said door casing.

2. A coke oven comprising an outer metal protecting plate, a door casing having a concave curvature toward the inside of said oven secured to said plate by fastening means, said fastening

means comprising a plurality of adjusting nuts and bolts cooperating with said plate to adjust the curvature of said casing, an inner and an outer bearing surface formed on said door casing, a door having a concave curvature toward the inside of said oven engaging said door casing, said door including vertical bars, a flexible plate rigidly connected to said bars, vertically spaced members attached to said plate, and a refractory lining supported by said spaced members, attaching means located at the upper end of said door, clamping means located at the lower end of said door, said clamping means forcing said door against said door casing thereby causing the flexible plate on said door to assume the configuration of said door casing, and sealing means disposed between said door and door casing, said sealing means including a flexible screen locked in said refractory lining and abutting against the outer bearing surface of said door casing, means mounted on said flexible plate forcing said flexible screen against said outer bearing surface of said door casing, and a second screen locked in said refractory lining and abutting against said inner bearing surface of said door casing, said flexible screen and said second screen effectively sealing said door against said door casing thereby providing a gas-tight structure.
